UNITED STATES PATENT OFFICE.

PIERRE PLANTINGA, OF CLEVELAND, OHIO.

DEVICE FOR CONTROLLING FLUIDS.

991,641.

Specification of Letters Patent.

Patented May 9, 1911.

Application filed May 12, 1909. Serial No. 495,476.

To all whom it may concern:

Be it known that I, PIERRE PLANTINGA, a citizen of the United States, resident of Cleveland, county of Cuyahoga, and State

5 of Ohio, have invented a new and useful Improvement in Devices for Controlling Fluids, of which the following is a specification, the principle of the invention being herein explained and the best mode in which 10 I have contemplated applying that principle, so as to distinguish it from other inventions.

15 My invention relates to devices for controlling the flow of air or other gases and particularly to the control of the air-supply 20 to the producer of a gas generating apparatus.

The object of the invention is to effect such air-control automatically, so as to produce a constant flow per minute through the 25 producer during the "blow", thereby uniformly maintaining the quantity and quality of the gas produced in the apparatus, as will be readily understood by those skilled in the art.

25 I am aware that means have heretofore been employed for definitely controlling the quantity and quality of the gas produced, wherein a gage for indicating the flow per minute of the air to the producer was em- 30 ployed, together with a manually operable valve. By these means, the attendant was enabled to manipulate such valve in accordance with the reading of the gage, so as to introduce a definite volume of air during the

35 interval of each "blow", regardless of fire and other conditions in the apparatus. In such previously employed apparatus, however, the flow per minute of the air was not constant, and varied from time to time.

40 Such variation was then manually corrected and only at such times as the attendant was aware of such variation and subsequently changed the valve opening to increase or decrease the flow of air accordingly.

45 My invention consists of means herein-after fully described and particularly set forth in the claim.

The annexed drawing and the following 50 description set forth in detail certain means embodying my invention, the disclosed means constituting but one of various mechanical forms in which the principle of the invention may be applied.

55 Figure 1 of the drawing illustrates dia- grammatically the gas producer of a gas- generating apparatus and duct for supply-

ing air thereto, arranged in accordance with my invention. Fig. 2 illustrates diagrammatically apparatus embodying my invention in a modified form.

60

Referring first to the structure illustrated by Fig. 1, the one end of the duct A is connected in the usual manner with the generator or gas-producer B, a suitable valve C being provided in the duct and near the 65 producer, whereby the latter may be connected with or cut off from the air-supply. The other end of the duct is connected with a suitable air-supply (not shown), such as a blower.

70

Located in the duct and intermediately of the valve C and the air supply is a resistance-plate D fixed to an oscillatory rod d, suitably mounted in the sides of the duct. This plate D is of a form such as to correspond with 75 the cross section of the duct, whereby it may be made to practically close the same when it occupies a position perpendicular to the duct's axis, after the manner of an ordinary butterfly valve. One end of the rod d projects some distance on the outside of the duct and has fixedly secured thereto an arm e. Articulating with this arm is a rod e' which is connected with the diaphragm e² of a pressure-operated device E of the usual 80 and wellknown construction, wherein two pressure-chambers are formed one upon each of the opposite sides of said diaphragm, and the latter is actuated as a result of an excess of pressure in one of the chambers 85 over that of the other. A suitable spring e³ is provided, together with adjusting mechanism therefor whereby its tension may be varied, as will be readily understood.

90

Located intermediately of plate D and the blower and in duct A, is a second resistance-plate H which is oscillatorily mounted in the sides of the duct. This plate, and its mountings, is arranged so that it may be set in various positions and retain its position 100 when so set. The outer end of the rod h upon which the plate is mounted is provided with a pointer h', which, in connection with a graduated segment a, indicates the position of plate F, as will be readily understood.

105

Tapping the duct A on the air-supply side of the resistance plate H is a pipe e⁴, which communicates with that chamber of the pressure-device which is opposite that traversed by the inner end of the rod e'. A similar pipe e⁵ taps the duct A on the producer

110

side of the resistance-plate and communicates with the other chamber of the device E.

When it is desired to "blow" the producer, valve C is opened wide and left in that position throughout the "blowing" operation. The tension of spring e^3 and the positions of the plates D and H are previously arranged so as to impart to the latter a position such that a given desired flow of air per minute will be effected past the plates, as is required to produce the previously determined necessary temperature in the producer, under given conditions of resistance to the flow of air through the apparatus. In the determination of the proper rate of flow, such rate may be varied by varying the tension of the spring or by changing the position of the plate D relatively to the arm e , or by changing the position of plate H.

Assuming now that the conditions in the apparatus change so as to offer a greater resistance to the flow of air therethrough, and that the pressure upon the air-supply side 25 of the resistance plate H is practically constant, such greater resistance will cause the difference in pressure upon opposite sides of the plate to decrease, and the diaphragm e^2 will consequently be flexed so as to move the rod e' to move the plate D so as to increase the orifice and thus increase the volume of air permitted to pass therethrough. The momentary change of the rate of flow of the air occasioned by the increase in the resistance to the flow through the apparatus is thus compensated for and the flow per minute through the producer brought to normal. It will therefore be noted that a variable orifice is provided in the duct, the variation 35 of the area of which is automatically controlled by the resistance to the flow of air through the apparatus, which may itself, as a whole, be considered a variable orifice. The area of the opening therefore increases 40 when the resistance to the flow of air through the generator increases. In other words, the greater the resistance to the flow

of air through the generator, the less the resistance offered by the resistance plate to the flow of air through the duct.

The resistance plate D and its automatically-operated actuating mechanism therefore acts as a governor to automatically maintain a constant flow of air per minute through the duct and hence into the producer.

In the application of my invention illustrated in Fig. 2, the automatically adjusted resistance plate D is placed intermediately of the air-supply and the resistance plate H. In this case the air supply is maintained at a substantially constant pressure, but the pressure of air between the two plates is caused to vary. The general result arising from the form of apparatus is however the same as in the previously described forms of my invention, as will be readily understood by those skilled in the art.

In both of the previously described applications of my invention, the air supply mechanism is arranged so as to produce a substantially constant pressure of air.

Having fully described my invention, what I claim and desire to secure by Letters Patent is:

In apparatus of the class described, the combination of the gas-generating apparatus; means for supplying air; a duct connecting the latter and said generating apparatus; a resistance plate in said duct adjustable so as to vary the resistance offered thereby to the flow of air through said duct; a second and movable resistance plate in said duct; a pressure-actuated member connected with said duct upon opposite sides of said first-named resistance plate; and means connecting the second-named resistance plate and said pressure-actuated member.

Signed by me, this 11th day of May, 1909.

PIERRE PLANTINGA.
